UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF TREATING LEATHER OR THE LIKE.

1,284,013.

Specification of Letters Patent.

Patented Nov. 5, 1918.

Application filed January 15, 1916, Serial No. 72,337. Renewed March 6, 1918. Serial No. 220,881.

To all whom it may concern:

Be it known that I, ERASTUS E. WINKLEY, a citizen of the United States, residing at Lynn, in the county of Essex and State 5 of Massachusetts, have invented certain new and useful Improvements in Methods of Treating Leather or the like; and I do hereby declare the following to be a full, clear, and exact description of the invention, such 10 as will enable others skilled in the art to which it appertains to make and use the same.

This invention relates to a method of treating leather, or like material, which is 15 particularly adapted to the preparation of leather lifts for boot and shoe heels, although its usefulness is not confined to the treatment of such pieces of leather.

In preparing heel-lifts for use it is common to remove more or less material from the flesh-side of the lifts in order to provide a smooth surface having no projecting fibers which would prevent the paste which secures it to other lifts in the heel from obtaining a firm hold. This operation is usually performed by splitting off a thin chip 20 of leather from the flesh side of the lift, and the machine employed for this purpose is commonly provided with two rollers between 25 which the stock is passed, and with a splitting knife which is fixed with its edge adjacent to the bite of the rollers. With this type of machine the stock may be forced against the knife and held securely in op-

erative relation thereto, and the position of the plane of cleavage may be accurately controlled. In such a machine the roller at the flesh side of the lift is usually mounted in an adjustable, but normally stationary, relation 30 to the knife, the width of the space between this roller and the knife being that which determines the even chip, or "fleshing" produced by the cutting operation. This roller is corrugated to act as a feed-roller. The 35 other roller is smooth and is pressed toward the grain side of the lift by springs the strength of which is adjustable. When an even amount of material is removed from the flesh side of the lift the operation is 40 commonly described as "fleshing" and the chip to be discarded passes between the knife and the stationary roller.

This type of machine is also used for evening lifts, *i. e.*, making them of an even thickness throughout. When so used the stationary roller is smooth and the spring pressed roller is corrugated and acts as a feed-roller. The knife and the stationary roller are relatively adjusted so as to produce the thickness of lift desired, and the lift is fed through in a reversed position, *i. e.*, with its flesh side against the spring-pressed roller. In this operation, which is commonly called "skiving," the chip to be discarded is of uneven thickness and passes between the knife 55 and the spring-pressed roller.

The present method may be practised successfully in performing either of these operations, or any analogous operation, but for the purpose of explanation it will be 60 described and illustrated in connection with its applicability to the fleshing of heel-lifts.

In fleshing heel-lifts, and more particularly top-lifts, it is desirable to avoid the removal from the lifts of any material beyond the flaky fibrous leather at the surface of the flesh side of the lift. Accordingly, it has heretofore been the practice, at least in the case of heel-lifts, to grade the lifts according to thickness, and then to flesh all 65 lifts of one thickness with a certain setting or adjustment of the adjustable feed-roller of the fleshing machine, the machine being later readjusted to properly care for the thickness of the next grade of lifts to be 70 fleshed.

The method thus described results in removing fleshings which in many instances are thicker than necessary. This does not utilize the material with the greatest economy. The poor results heretofore obtained are due to the fact that the lifts, or other pieces of leather, are variable not only in thickness but also in density. The pressure to which the leather is subjected between the 75 rollers of the fleshing machine, and which is a necessary incident to the fleshing operation, will obviously cause a degree of compression in the leather, and a localized reduction in its thickness at the point between the 80 rollers which will depend, for any given pressure, upon the density of the leather. If the distance between the stationary feed-roller and the knife be adjusted for a de-

sired thickness of chip and two lifts of the same thickness, but of different densities, be passed through the machine, the resultant lifts will vary in thickness instead of being 5 of the same thickness, that of the lesser density having a thicker chip removed.

The reason for this, assuming that the springs for pressing the yielding roller have been set to such tension as to cause the machine to properly operate on the lift of greater density, is that the pressure exerted on the lifts by the springs of the yielding roller will locally compress the lift of lesser density to a thickness less than its normal 15 thickness and in so doing will force some of the material, which should be left in the portion of the lift which is to be retained, into the space between the knife and the stationary roller, which material is then removed 20 by the knife. The lift of greater density, for which the springs have been adjusted, is not compressed locally and only the thickness of chip for which the knife is set is removed. It is highly desirable, as is well 25 known to those skilled in the art, that the body of the lift, after the fleshing operation, be of the greatest thickness that can be obtained.

The object of the present invention is to 30 avoid the disadvantage of the method just described, and to provide a method of treating leather for the purpose described which will produce uniform results and the greatest economy in material.

35 The present inventor has discovered that in order to produce uniform results without constant readjustment of the fleshing machine, and without waste material, it is necessary that for each adjustment of the machine the leather which is operated upon should be uniform not only in thickness but also in density, and accordingly as a first 40 step of the present method, the lifts are graded, before being fleshed, as to both thickness and density. The lifts are thus separated into grades each of which is uniform in both of these characteristics. As a result 45 all the lifts of any one of the grades so produced is subjected to the fleshing operation under uniform conditions, that is to say, 50 under such conditions as are encountered, for example, with a particular adjustment of a fleshing machine, in case such a machine be used for the performance of this second step 55 in the method.

The invention consists in the method of 60 treating pieces of leather, or like material, for example heel lifts, which are heterogeneous as to both thickness and density, in such a manner that after treatment the greatest possible thickness is retained in each piece, the preferred manner of practising 65 which is defined in the appended claims.

The invention will most readily be understood 70 by a reference to the accompanying

drawings, illustrating the preferred manner of practising the invention, in which:

Figure 1 illustrates, diagrammatically, the manner in which the heel lifts, or other pieces of leather, are graded prior to the fleshing operation, and

Figs. 2 and 3 illustrate diagrammatically the fleshing operation as performed by an ordinary fleshing machine, showing the effects of the old method on lifts of like thickness but of different densities.

The grading of the lifts may be performed in any manner which will produce grades uniform in both thickness and density. Generally, it will be necessary to subject each lift to sorting or grading operations, one directed toward the determination of thickness, and the other toward the determination of density, although it may be possible to determine both these characteristics by a simultaneous operation. Generally speaking, it is immaterial whether the density or the thickness be first determined, but assuming that the lifts are first caliper for thickness, they will be 80 separated into preliminary grades in accordance with thickness alone, all the lifts of any particular grade being of the same thickness regardless of their density. This step may be performed with the Ross-Moyer 85 or any other leather measuring machine. Each of the preliminary grades so produced will then be subjected to a density determination, by which the lifts in each of the 90 grades characterized by thickness will be 95 separated into a number of final grades all of the same thickness but each of a different density. This step may be performed with the machine disclosed in an application for United States patent Serial No. 389,030, 100 filed April 6, 1912 by the present inventor. Each of these final grades will then contain only lifts uniform in both thickness and density, and the lifts of each grade may 105 then be passed through the fleshing machine 110 with a given adjustment adapted for that particular thickness and density of leather.

Fig. 1 illustrates the steps of the grading operation by which the lifts, or other pieces of leather, are first divided into preliminary 115 grades in accordance with thickness and are then divided into final grades in accordance with density as well as thickness. For illustrative purposes nine lifts of two different densities are indicated, and designated by the reference numbers 1 to 9 inclusive, their thickness being exaggerated and their density being indicated by section lines, those more closely lined being of the greater density. In the left-hand column 120 of Fig. 1 the lifts are shown as heterogeneous with respect to thickness and density, as they may come at random from the stock-cutting machine by which they are produced. In the second column the lifts 125

are shown as graded for thickness, being shown, arbitrarily, as divided into three preliminary grades, each of which includes three lifts of two different densities. In the 5 third column of Fig. 1 the lifts are shown as finally graded. The lifts 1, 5 and 9, which constitute the preliminary grade of least thickness, have been divided into two final grades, of which grade A contains a 10 lift 5 of lesser density and grade B two lifts 1 and 9 of greater density. The lifts 3, 4 and 7, constituting the preliminary grade of medium thickness, have been divided into two final grades in which grade C includes 15 the lift 4 of lesser density, and grade D includes the lifts 3 and 7 of greater density. Grades E and F will be understood without further explanation.

Figs. 2 and 3 illustrate the undesirable 20 result of the fleshing operation as performed, for example, upon grade C in the case of Fig. 2, and upon grade D in the case of Fig. 3 when the fleshing machine, in accordance with the usual methods, has a fixed 25 adjustment for all lifts of the same thickness. This adjustment is secured by regulating the distance between the stationary upper feed roller R and the knife K. A screw T threaded into the journal box of 30 the roller R is shown, diagrammatically, as the means for producing this adjustment. The lower roller U is shown as pressed upwardly by springs, one of which is shown at V. A stop on the frame, as usual, determines the upward limit of movement of this 35 roller. The spring V, it will be assumed, is so adjusted as to properly care for lifts having a density of grade D, which is greater than the density of the lifts in 40 grade C.

Since the material of grade C is less dense than that of grade D, although the lifts are of the same thickness, it will be compressed to a less thickness between the rollers under 45 the pressure of the springs V than will the material of grade D, and the lift of grade C will, for the reasons hereinbefore explained, be left thinner than it should be after the fleshing operation. This results in a waste 50 of stock in all lifts of the same thickness as those in grade D but of a lesser density.

This disadvantage is overcome by the present method as, after the grading of the lifts in the manner described has been completed, all lifts of the same density, for example all lifts in grades B, D and F, may be properly fleshed, that is, with the greatest saving of stock, with a single setting of the machine. In changing from one grade to 55 another of substantially different thickness or density adjustment of both the stationary roller and the knife relative to the yielding roller may be desirable to insure a proper feed.

60 In performing a skiving operation, after

grading the pieces in the manner described, for skiving pieces of any particular density, for example, those in grades A, C and E, having first set the springs V to a strength commensurate with the density of the 70 pieces, it is only necessary to see that the stationary roller is adjusted a proper distance from the knife to obtain the maximum thickness from any grade, and all resultant pieces will be of an equal thickness. When 75 further pieces of greater or less density are skived a corresponding adjustment of the strength of the springs V is made.

While the invention has been described as particularly useful in the fleshing operation, it will be apparent that it may also be useful in connection with any operation by which a piece of leather is divided into two or more layers or splits, each of which may be of a useful thickness, and the 80 method may also be applicable to the splitting of material other than leather, but having the same variable characteristics of thickness and density, though no such material is now known to the inventor. 90

By the method herein described the operator is certain that each lift after being fleshed will compress to a definite known thickness, whereas in the method now used the thickness to which the lift will compress 95 after fleshing is unknown.

It is manifest, moreover, that the advantageous and novel features of applicant's preliminary grading operation are useful, adaptable and desirable in connection with 100 subsequent operations, other than splitting, that are performed in the manufacture of heels. The invention, therefore, as set forth in certain of the appended claims, is not restricted in any sense to the character and 105 nature of the subsequent operation, but said claim is intended to be of such scope as to cover applicant's grading operation to whatever useful purpose it may be put.

Having thus described the invention and 110 the preferred manner of practising it, it is definitely stated in its true scope in the following claims.

What is claimed as new, is:

1. The method of treating pieces of 115 leather, or like material, which comprises the step of grading a plurality of pieces which are heterogeneous as to both thickness and density so as to assemble in separate grades those pieces which are uniform as to 120 both thickness and density, and the step of subjecting the pieces of each grade so assembled to a splitting or like operation under uniform conditions.

2. The method of treating pieces of 125 leather, or like material, which consists in sorting the pieces into grades according to thickness and then sorting each thickness grade into sub-grades according to density, or vice versa, and then splitting the pieces in 130

each sub-grade white subjected to substantially the same pressure.

3. The method of grading heel-lifts or the like, that are heterogeneous as to both thickness and density, which consists in determining the thickness and density of said heel-lifts, and in sorting said heel-lifts into separate grades each containing only heel-lifts which are uniform as to both thickness and density.

4. The method of fleshing or skiving heel-

lifts, or the like, which consists in sorting a plurality of lifts which are heterogeneous as to both thickness and density into separate grades which are uniform as to both of these characteristics, and then removing a fleshing or skiving chip from the lifts, grade by grade, under varying pressures according to the density variation of each grade.

ERASTUS E. WINKLEY.
